UNITED STATES PATENT OFFICE.

ALEXANDER MALCOLM, OF GRANGEMOUTH, SCOTLAND.

STEAM-TRAP.

No. 915,780.

Specification of Letters Patent. Patented March 23, 1909.

Application filed August 7, 1907. Serial No. 387,402.

To all whom it may concern.:

Be it known that I, ALEXANDER MALCOLM, engineer, a subject of the King of the United Kingdom of Great Britain and Ireland, and resident of 19 Charlotte street, Grangemouth, Scotland, have invented new and useful Improvements in Automatic Siphon Steam-Traps, of which the following is a specification.

10 This invention relates to an automatic steam trap for draining water from steam pipes and cylinders, due to condensation and wet steam.

Figure 1 shows a sectional elevation of the 15 improved automatic siphon steam trap. Fig. 2 is a sectional plan view of the same.

The upper end A of the steam trap, as shown, is designed to be screwed into the pipe or cylinder to be drained of water so as 20 to depend approximately vertically therefrom, and the lower screwed end B may be open to the atmosphere or into another length of tubing for conducting the drainage water to any desired point. The steam trap 25 is formed with a main chamber or catch basin a having a curved bottom wall for the purpose presently to be explained, and adjacent to the bottom wall is a lateral port or opening c³ through which the water of condensation may pass into the siphon discharge passage. Surrounding the port or 30 opening c³ is a seat c⁴ of "woodite" or other like suitable composition to afford the proper seat for the ball valve.

35 b is a ball valve of any buoyant material, such as cork, or of hollow metal such as aluminum or brass. The ball b is free within the chamber a so as to rise in the chamber and float upon the water that collects therein. Normally the ball b rests against the 40 valve seat c⁴ of the valve opening c³ to close the outlet from chamber a into the siphon passage way. The shape of the bottom wall of chamber a is such with relation to the seat 45 of the port c³ that the ball will be held by its engagement with the bottom wall into closed engagement with the valve seat. In addition to this the chamber a being in open communication with the steam pipe or cyl-

50 iner to which the trap is attached, it will be observed that the pressure of the steam in the pipe or cylinder will also tend to hold the ball b in closing contact with the seat of the outlet port.

55 Formed in the body of the steam trap at

one side of the main chamber a are the parallel vertically arranged legs c and c² of the siphon passage C. The inner siphon leg c is closed by the bottom wall c' just below the port c³ which leads into it from the chamber 60 a; while the other siphon leg c² leads into the discharge or outlet end b of the trap.

A rotary valve D may be provided as shown with its stem threaded through the outer wall of the casing of the trap in alignment 65 with the port c³, so as to regulate the size of the opening through port c³ or to engage the ball to force it away from its seat in said opening. This valve D may also prove useful in entirely closing up the opening c³ to 70 prevent the escape of steam in the event of the float or ball b being out of order.

It will be observed that in operation the water of condensation collecting in the main chamber a will float the ball b away from the port c³ and allow water of condensation to pass through said opening into the leg c of the siphon passage, from which it is discharged into the leg c², the ball being again re-seated upon the port c³ after the water of 80 condensation has passed from chamber a.

What I claim is:

1. A steam trap having a main chamber a and a siphon discharge passage c, c² in communication with said main chamber through 85 a lateral port c³, and a float b in the chamber a, adapted to be seated upon said lateral port c³, substantially as set forth.

2. A steam trap having a main chamber a formed with a curved bottom wall and a lateral escape port c³, a float valve within the chamber a adapted to be seated against said escape port by its engagement with the bottom wall of said chamber a, and a siphon discharge passage into which said escape port 95 leads.

3. A steam trap having a main chamber a and a siphon discharge passage c, c² communicating with said main chamber through an escape port c³, in combination with float 100 valve b within casing a adapted to be seated in said escape port c³, and a valve D suitably mounted in the casing in position to control the discharge port c³ independently of the ball valve.

ALEXANDER MALCOLM.
